PET SNOW SUIT

Constance Giordano, 110—20 71st Road,
Forest Hills, N.Y. 11375

Filed Mar. 3, 1970, Ser. No. 21,721

Term of patent 14 years

Int. Cl. D30—04

U.S. Cl. D30—37

FIG. 1

FIG. 2

FIG. 3

FIG. 4

FIG. 5

FIG. 1 is a top plan view of a pet snow suit embodying my new design;

FIG. 2 is a side elevational view of a pet snow suit embodying my design;

FIG. 3 is a front elevational view of said pet snow suit;

FIG. 4 is a rear elevational view of said pet snow suit; and

FIG. 5 is a bottom plan view of said pet snow suit. I claim:

The ornamental design for a pet snow suit, substantially as shown.
